CLAIM

The ornamental design for a digital video camera with a connector, as shown and described.

DESCRIPTION

FIG. 1 is a front perspective view of a digital video camera with a connector;

FIG. 2 is a back perspective view thereof;

FIG. 3 is a front perspective view thereof, with the connector extended;

FIG. 4 is a back perspective view thereof, with the connector extended;

FIG. 5 is a right side view thereof, with the connector extended;

FIG. 6 is a left side view thereof, with the connector extended;

FIG. 7 is a top view thereof, with the connector extended;

FIG. 8 is a bottom view thereof;

FIG. 9 is a front view thereof, with the connector extended; and,

FIG. 10 is a back view thereof, with the connector extended.

The portions of a camera in broken lines are shown to illustrate environment only and form no part of the claimed design.
